UNITED STATES PATENT OFFICE.

JOHN SWEENEY, OF CHICAGO, ILLINOIS.

IMPROVED TOBACCO-PRESS.

Specification forming part of Letters Patent No. 28,912, dated June 26, 1860.

To all whom it may concern:

Be it known that I, JOHN SWEENEY, of Chicago, in the county of Cook and State of Illinois, have invented a new and Improved Press for Compressing Stearine, Paper, Tobacco, and other Substances; and I do hereby declare that the following is a full, clear, and exact description of the same, reference being had to the annexed drawings, making a part of this specification, in which—

Figure 1 is a side elevation of my invention. Fig. 2 is a front elevation of the same.

Similar letters of reference indicate corresponding parts in the two figures.

This invention consists in the employment or use of a worm-wheel and screw, combined with chains, stirrups, a cross-head, and guides, arranged as hereinafter fully shown and described, whereby a very simple, efficient, compact, and powerful press is obtained, and one that may be manipulated by any one of ordinary ability, the invention being designed for manual operation.

To enable those skilled in the art to fully understand and construct my invention, I will proceed to describe it.

A represents a base or box supported at a suitable height, and having two uprights, B B, secured to it, which uprights may be of cylindrical form, to serve as guides for one or more followers or platens, C, which are placed between the uprights and notched at their ends to receive the same.

D is a shaft, which is placed transversely under the bar or box A in suitable bearings, and has a worm-wheel, E, on one end, into which a screw, F, on the shaft G gears. On the outer end of this shaft G a ratchet, H, is placed, and I is a lever forked at one end, and provided with a pawl, a, which engages with the ratchet when the forked end of the lever is fitted over the ratchet and on its shaft G.

To the shaft D, and at each side of the base or box A, there is attached a chain, J, to the upper end of which stirrups K are attached—one to each. The stirrups K are fitted over the ends of a cross-head, L, which is placed on the uppermost follower C.

From the above description it will be seen that by turning the shaft G, through the medium of the lever I, pawl a, and ratchet H, motion will be communicated to the shaft D through the medium of the screw F and worm-wheel E, and as the shaft D is rotated the chains J will be wound upon it, and the cross-head L pressed down on the uppermost follower C, and the substance beneath the follower compressed.

In certain cases, where juices or oils are to be expressed from substances, the latter may be put into bags placed between a series of followers C, as shown in red in the drawings, and in such cases the box A will catch the fluid.

The whole device, it will be seen, is extremely simple and efficient, may be constructed at a small cost, and monopolizes but little space. It has been practically tested for compressing stearine, and has been found to answer an admirable purpose.

I do not claim separately any of the parts herein described; but

I do claim as new and desire to secure by Letters Patent—

The combination of the worm-wheel and screw E F, chains J, cross-head L, guides B B, follower C, one or more, and base or box A, with the ratchet and lever H I, or their equivalents, arranged for mutual action, as and for the purpose set forth.

JOHN SWEENEY.
